(57) **CLAIM**

The ornamental design for a rack mounted audio equipment, as shown and described.

DESCRIPTION

FIG. 1 is a front upper perspective view showing the rack mounted audio equipment of Applicants' invention.

FIG. 2 is a front elevation of the rack mounted audio equipment of Applicants' invention.

FIG. 3 is a right side elevation of the rack mounted audio equipment of Applicants' invention, the left side being a mirror image thereof.

FIG. 4 is a rear elevation of the rack mounted audio equipment of Applicants' invention.

FIG. 5 is a top view of the rack mounted audio equipment of Applicants' invention.

FIG. 6 is a bottom view of the rack mounted audio equipment of Applicants' invention.

FIG. 7 is a front lower perspective view showing the rack mounted audio equipment of Applicants' invention.

FIG. 8 is a rear upper perspective view showing the rack mounted audio equipment of Applicants' invention; and,

FIG. 9 is a partial front upper perspective view showing the rack mounted audio equipment of Applicants' invention, with an access door thereof in an open position.
